UNITED STATES PATENT OFFICE.

ARTHUR W. BENSMAN, OF BUFFALO, NEW YORK.

STERILIZER.

Application filed February 10, 1920. Serial No. 357,606.

To all whom it may concern:

Be it known that I, ARTHUR W. BENSMAN, a citizen of the United States, residing at Buffalo, in the county of Erie and State of New York, have invented certain new and useful Improvements in Sterilizers, of which the following is a specification.

My invention relates to sterilizers, and more particularly to that type of sterilizers 10 adapted for barbers' use.

One of the objects of my invention is to provide a sterilizer having individual compartments for towels and wherein said compartments are arranged in vertical, horizontal 15 or other series so that each series may be assigned to each of a number of barbers employed in a barber shop, assuring absolute responsibility for the condition in which towels are maintained.

Another object of my invention is the provision of a sterilizer in which steam is employed for sterilizing purposes, and in which provision is made for returning the water of condensation from the steam back to the 25 source from which the steam was generated.

Another object of my invention is to provide a sterilizer having a door, with means for collecting the water of condensation from the door and thus prevent dripping of 30 the water onto the floor when opening the door.

A still further object of my invention is, in a sterilizer having a water reservoir and a sterilizing chamber having a door and being 35 in communication with said water reservoir, the provision of means to shut off communication between said water reservoir and said sterilizing chamber when opening said door and to open up communication 40 therebetween when closing said door.

With these and other objects in view, the invention consists in the novel features of construction and in the arrangement and combination of parts to be hereinafter described and more particularly pointed out in the subjoined claims.

In the drawings:—

Fig. 1 is a vertical section through a sterilizer showing my invention in a representative form.

Fig. 2 is a vertical section taken on line 2—2, Fig. 1.

Fig. 3 is an enlarged vertical section taken on line 3—3, Fig. 2.

Fig. 4 is a horizontal section taken on line 4—4, Fig. 2.

Fig. 5 is a detached perspective view of one of the towel-holding tubes or compartments.

Fig. 6 is a front elevation of a portion of 60 a sterilizer embodying one of the features of my invention in modified form.

Fig. 7 is a horizontal section taken on line 7—7, Fig. 6.

Fig. 8 is a vertical section through the 65 lower end of the door shown in Fig. 6.

Reference being had to the Figs. 1 to 5, 10 designates a casing or cabinet of any suitable form, that shown being of rectangular formation and having a base 11 within 70 which a suitable heater may be placed for heating the bottom of said casing or cabinet.

The cabinet is divided by a horizontal wall or partition 12 into two compartments 13, 14, the compartment 13 being the sterilizing 75 chamber or compartment while the compartment 14 is the steam generating chamber or water reservoir in which a quantity of water is to be placed so that steam will be generated in the lower portion of the cabinet and 80 delivered into the sterilizing chamber 13; and for this purpose the wall or partition 12 is provided centrally with an opening into which an upstanding wall or sleeve 15 is fitted and fastened, this sleeve being flanged 85 outwardly at its lower end, as at 16, to engage the under side of the wall or partition 12 around the opening therein, and it is also provided with a circular external rib 17 adapted to bear against the upper side of 90 said wall or partition. In this manner the upstanding wall or sleeve 15 is securely fastened into the wall or partition, and while this is the preferred construction, it is apparent that said upstanding wall or sleeve 95 may be otherwise fastened to the wall or partition 12, or may be formed integral therewith, as may be desired.

The upstanding wall or sleeve 15 is preferably cylindrical in cross section and provided with a plurality of openings 18 serving as steam-outlets. Surrounding said upstanding wall or sleeve is a cylindrical valve 19 bearing with its lower edge against the external rib 17 and having the upper marginal portion of the upstanding wall or sleeve 15 bent over the upper marginal portion thereof, as at 20, so that said valve is retained against longitudinal movement but is permitted to rotate. This cylindrical 110 valve is also provided with a series of openings 21 which are at times adapted to regis-

ter with the openings 18 in the upstanding wall or sleeve 15.

Lying against the upper edge of the upstanding wall or sleeve 15 is a closure plate 5 or cap 22, which may be secured to said wall or sleeve or be laid loosely thereon, its purpose being to close the upper open end of said upstanding wall or sleeve and cause steam generated in the water reservoir 14 to be directed outwardly through the openings 18, 21, when said openings are in registration.

The upstanding wall or sleeve 15 is provided with an elongated opening 23, and 15 the valve 19 is provided with an inwardly-extending socket 24 which projects through said elongated opening. Within said socket is a spring 25 which bears against the inner end of a stud 26 limited in its outward movement by a suitable wall or retainer 27 in said socket, against which a shoulder on said stud at the inner end thereof bears. Said stud has at its outer end an enlargement or 20 head 28 which is formed conical at its outer 25 extremity, as at 29.

The front wall of the cabinet has an opening 30 formed therein which is closed by a door 31 hinged, as at 32, to one side of the cabinet. This door comprises a suitable 30 channel-shaped frame 33 forming a large panel opening in which a plate of glass 34 serving as a transparent panel is inserted, said glass being held in place by a retainer strip 35 within the channel of said frame. 35 The lower horizontal channel member of said channel-shaped frame has a metallic flat strip 36 placed therein which may be termed a false bottom for said channel member, and this strip or false bottom is inclined 40 from opposite side edges of the door to a common intermediate point 37, the inner wall of the lower channel member of said door frame, the lower horizontal portion of the retainer strip and said flat strip or false 45 bottom 36 serving to form a trough or collector into which the water of condensation from the steam gathered on the inner side of the door will trickle. The inner side wall of the lower channel member of said door 50 frame is provided with an opening 38 at the lowermost point of said trough, and fastened to said inner wall in registration with said opening is a segmental tube 39, substantially on an arc of a circle having the hinge 55 of the door as its axial point, said tube having an enlargement or collar 40 at its inner or free end, as clearly shown in Fig. 4, which is adapted to engage the conical end of the bolt 26 when opening the door to cause the 60 cylindrical valve 19 to rotate on the upstanding cylindrical wall or sleeve 15 in the lower end of the sterilizing chamber.

When the door of the cabinet is closed, the segmental tube 39 is in the position shown 65 in Fig. 4, and the socket 24 of the valve at

the rear end of the elongated opening 23, and when opening the door the enlargement or collar 40 on said tube is brought in engagement with the conical end of the bolt 26 and is retained in engagement therewith 70 while moving the inwardly-directed socket 24 of the valve forwardly, until said socket engages the front or opposite end of the elongated opening 23 in said wall or sleeve, at which point said socket with its bolt will 75 be stopped, as indicated by dotted lines in Fig. 4. Further outward movement of the door will cause the enlargement or collar 40 on the segmental tube to depress the bolt against the action of the spring 25 within 80 the socket 24, thus permitting the enlargement or collar to pass forwardly beyond the bolt so as to enable the door to be opened to the desired extent.

When the door is open, as shown in dotted 85 lines in Fig. 4, the water of condensation cannot drip upon the floor and create unsanitary conditions. Moreover, any water of condensation collected in the trough at the bottom of the door will pass through the 90 segmental tube 39 and be delivered by the latter into the sterilizing chamber.

When closing the door, the enlargement or head of the segmental tube will again engage 95 the conical end of the bolt 27 and cause opposite rotation of the cylindrical valve until the inwardly-extending socket 24 strikes the return or rear end of the elongated opening 23 in the upstanding wall or sleeve 15, at which time the bolt will be forced inwardly 100 against the action of the spring 25 in said socket, and after the enlargement or collar has cleared the bolt, the spring will again project the latter, the enlargement or collar passing beyond the bolt during the final 105 closing movement of the door and when the door is closed the enlargement or collar will have reached the point shown in Fig. 4.

It is apparent therefore that the inner end of the segmental tube is always within the 110 lower end of the sterilizing chamber whether the door is opened or closed, so that the water of condensation gathering on the inner side of the door will be delivered through said tube at all times.

The water reservoir 14 is provided with the usual filling opening 41, in front of which a filler cup 42 is secured to the casing. In this manner the water within the water reservoir can easily be maintained at the desired level, preferably in line with the lower end of the filling opening 41. In preferred construction this filling cup 42 is located in the front wall of the cabinet midway between opposite sides thereof, and directly 125 beneath the door.

Secured to the opposite side walls of the cabinet are two ledges 43 in the form of angle-shaped members, which are fastened in place a suitable distance above the hori- 130

zontal wall or partition 12 serving as the bottom of the sterilizing chamber.

Resting on the ledges 43 is a support 44, which may be in the form of an open-sided 5 casing comprising a top wall 45, a bottom wall 46 provided with steam openings 47, and front and rear walls 48, 49, respectively. This support in its preferred form is therefore constructed of sheet metal having two 10 spaced supporting members, which the front and rear walls 48, 49 may be designated. The front wall has a plurality of openings 50 formed therein, and the rear wall has a like number of openings 51. The openings 15 in the front and rear walls are paired; that is to say, each opening in the front wall is adapted to co-operate with an opening in the rear wall, for a purpose to presently appear. These openings may be arranged 20 in any desired manner, but I have shown them formed in the front and rear walls at regular intervals, both horizontally and vertically, so that they may be said to be formed in either vertical or horizontal 25 series, and in these openings are supported individual towel-receiving compartments 52, which are in the form of cylindrical tubes having opposite ends fitted in the openings 50, 51, each tube being retained in a pair of 30 openings in the front and rear wall. By preference, the openings in the front wall are situated in a plane slightly higher than the mating openings in the rear wall so that the tubes are inclined rearwardly, as best 35 shown in Fig. 2.

Each of the tubes has the metal forming the same dented inwardly at its highest point in substantially V-shape so as to form what may be termed a gathering groove or 40 trough 53, and at its lowermost point each of said tubes has an outwardly extending V-shape rib 54, both the trough and the rib being extended from end to end of the tube, the rib of each tube being directly above a 45 trough of the tube directly beneath.

Towels indicated by the numeral 55 in Fig. 1 are adapted to be placed in the tubes or compartments 52, one or more towels for each tube; and where a number of barbers are employed in a shop, there may be a 50 series of these tubes or compartments assigned to each barber. In the arrangement shown in Fig. 1, there are five horizontal rows of tubes or towel-receiving compartments and four vertical rows. Assuming that there are five barbers employed in a shop, each barber may have a horizontal row assigned to him, or if there are four barbers employed, each may have one of 55 the vertical rows assigned to him, but this division may be otherwise arranged, as the tubes or compartments may be numbered consecutively and each barber given a certain number of tubes. Under any of these 60 arrangements, however, absolutely sanitary 65

conditions are assured and full responsibility placed for the lack of such conditions.

The support 44 has its front wall spaced from the door of the cabinet and its rear wall from the rear wall of the cabinet so 70 that the steam entering the sterilizing chamber may pass upwardly in rear and in front of the support, and due to the bottom of the support having the openings 47, the steam may also pass upwardly through 75 these openings and up between the tubes or towel compartments and also up alongside the two outer vertical series of tubes or compartments. The steam passing up in front and in rear of the support will enter the 80 tubes or compartments from opposite ends so as to sterilize the towels within the compartments, and the steam passing up alongside the tubes or compartments may enter the same through perforations 56 which are 85 arranged in two series at opposite sides of the trough lengthwise of each tube or compartment, thus assuring thorough sterilization of the towels within the compartments.

In the modification shown in Figs. 6 to 90 8, the cabinet has filling openings 57 formed in two walls near their meeting angles, and a filling cup 58 fitted to the exterior of these walls so as to surround said openings, this cup being situated directly beneath the horizontal edge of the door, as clearly shown in Fig. 6.

In this modification, the frame 33 of the door has its lower frame member provided with a discharge opening 59, and in said 100 lower frame member is a straight strip or false bottom 60 inclined from the outer or free edge of the door towards the hinged edge thereof so as to direct the water of condensation collected in said lower frame member, which serves as a trough, to said discharge opening, from which it is directed into the filling cup 58, the discharge opening 59 being directly above said filling cup. In this manner the water of condensation 105 from the door will at all times be delivered into the filling cup, and from the latter through the filling openings into the water reservoir of the sterilizer, whether the door is opened or closed.

From the foregoing it will be apparent that the details of this invention may be modified in various ways without departing from the scope of the same or sacrificing any of the advantages thereof.

Having thus described my invention, what I claim is:

1. A sterilizer comprising a cabinet having a water reservoir supplied with water to be heated to generate steam, a sterilizing 125 chamber in communication with said water reservoir to receive the steam therefrom, said sterilizing chamber being separated from said reservoir by a wall or partition having an opening therein, and means to open and 130

close said opening, said sterilizing chamber having an opening and a hinged door to close said last-mentioned opening, and means to cause the opening in said wall or partition to be closed when opening said door.

2. A sterilizer comprising a cabinet having an opening and a door for closing said opening, said cabinet having a water reservoir and a sterilizing chamber separated

10 from said water reservoir by a wall or partition having an opening therein and an upstanding wall fitting into said opening, said upstanding wall having a steam opening therein, a valve for opening or closing the 15 steam opening in said upstanding wall, and means projecting inwardly from said door to cause movement of said valve so as to close the steam opening in said upstanding wall.

3. A sterilizer comprising a cabinet having an opening and a door for closing said opening, said cabinet being divided to form a water reservoir supplied with water to be heated to generate steam and a sterilizing chamber above said water reservoir separated from the latter by a wall or partition having a cylindrical upstanding wall provided with a plurality of openings, a closure closing the upper end of said cylindrical wall, a valve surrounding said cylindrical wall, and having openings therein adapted to register with the openings in said cylindrical wall, and means on said door adapted to actuate said valve to close the openings in said cylindrical wall when opening said door.

4. A sterilizer comprising a cabinet having a water reservoir adapted to contain water to be heated to generate steam, a sterilizing chamber above said water reservoir separated from the latter by a horizontal wall or partition having an open-ended sleeve extending upwardly therefrom into said sterilizing chamber, said sleeve having a plurality of openings therein, a cylindrical valve surrounding said sleeve and having openings corresponding to the openings in said sleeve, and a closure at the upper end of said sleeve, said sterilizing chamber having an opening in one of its side walls and a door hinged thereto to open or close said opening, said door having a trough at its lower end to collect the water of condensation from the inner side of said door and a curved tube extending inwardly from said trough to direct the water into the lower end of said sterilizing chamber and to close and open said cylindrical valve.

5. A sterilizer comprising a cabinet having a water reservoir, and a sterilizing chamber separated from said water reservoir

by a wall or partition having an upstanding sleeve provided with openings around the same and an elongated slot, means for closing the upper end of said sleeve, a cylindrical valve surrounding said sleeve and having 65 openings corresponding to the openings in said sleeve and having a socket extending through the elongated slot of said sleeve and a spring-projected member in said socket, a door hinged to said cabinet for gaining 70 access to the interior of said sterilizing chamber, and a curved element on said door adapted to engage the spring-projected member of said valve for opening and closing said valve.

6. A sterilizer having a sterilizing chamber, a support within said chamber comprising top and bottom walls and two opposite walls connecting said top and bottom walls, each of said walls having a plurality of vertically-disposed series of openings therein with the openings in one wall paired with those of the other and in a lower plane, and a tube having its ends retained in each pair of openings and being provided with 80 means to cause water of condensation to be directed lengthwise along said tube and to the exterior of one of said opposite walls.

7. A sterilizer having a sterilizing chamber, a support within said chamber having top and bottom walls and opposite vertical walls connecting said top and bottom walls, each of said vertical walls having a vertical series of openings therein, the openings in said opposite vertical walls being paired and 90 one of each pair being in a lower plane than its mating opening, and a tube having its ends retained in each pair of said openings and being provided with a trough along its highest point and a rib along its lowermost 100 point, the rib of each tube being directly above the trough of the tube next below and each of said troughs being adapted to direct the water to the outside of one of said vertical walls.

8. A sterilizer having a sterilizing chamber, a support removably retained within said chamber and having spaced supporting elements, and a vertical series of tubes inclined within said support, each tube receiving support at opposite ends from said supporting elements and having a trough along its highest point, a V-shaped rib along its lowermost point and a series of steam inlet openings along opposite sides of said trough, the ribs of each tube being disposed to lead water of condensation into the trough of the next lower tube of the series.

In testimony whereof I affix my signature.

ARTHUR W. BENSMAN.
